PISTON FOR AN INTERNAL COMBUSTION
MOTOR

Elmer C. Long, Grosse Pointe Park, Mich.

Application August 22, 1932, Serial No. 629,805

8 Claims. (Cl. 309—13)

This invention relates to certain improvements in aluminum alloy pistons for internal combustion motors and has for its primary object to provide improved take-up means within 5 the skirt for taking up or holding in the piston skirt under thermal conditions thus preventing overexpansion of the skirt.

Another object of the invention is in providing a piston having a skirt separated from the 10 head with improved means for supporting the skirt from the head.

A further object of the invention is in providing a piston having a skirt of a pair of opposing sections with improved resilient yieldable 15 means supporting the sections interiorly of the piston.

A still further object of the invention is in providing a piston with a flexible skirt with transversely disposed portions of material different 20 from the skirt, which are associated with the interior web structure of the piston in an improved manner.

Another still further object of the invention is in providing a piston with a flexible skirt and 25 improved means co-actable with the skirt for providing a piston skirt capable of operating with less clearance.

Other and further objects will appear in the specification and be specifically pointed out in 30 the appended claims, reference being had to the accompanying drawing, exemplifying the invention, and in which:—

Figure 1 is a transverse vertical section of this improved piston taken through the thrust 35 sides of the piston.

Figure 2 is a transverse vertical section taken approximately on the line II—II of Fig. 1.

Figure 3 is a horizontal section taken approximately on the line III—III of Fig. 1.

Figure 4 is a horizontal section taken approximately on the line IV—IV of Fig. 2.

The accompanying drawing discloses a head 1 having a depending side wall 2 for the support of packing ring grooves 3 and extending across 45 the head interiorly thereof are a pair of transversely disposed webs 4, the outer ends of said webs, of which there are a pair, joining at their ends with the side wall of the head and depending downwardly at their ends into legs 5, the 50 pending ends of said legs supporting respective pin bosses 6.

The skirt 1 of the piston comprises a pair of opposing sections 8 and 9, said sections being separated from the head by respective transverse 55 gaps or slots 10 and from each other by a longi-

tudinal gap 11 and the gap 12 on each pin boss side of the skirt which surround or encompass the legs 5 and respective pin bosses 6.

The section 8 of the skirt is on the power thrust side of the piston and is supported from the head 1 and the pin bosses 6 by a pair of webs 13 which extend downwardly from the head but are free from engagement with the side wall 2 of the head and are united in right angular disposition with one of the transverse webs 4 and its relatable legs 5 and pin bosses 6 as shown in Figs. 1 and 3.

The section 9 is on the compression thrust side of the piston, said section 9 being supported from the pin bosses 6 by a pair of right angular formed webs 14, each of which extend from a respective pin boss to the section 9. Each right angular web 14 is disposed so that the leg 15 of each web 14 will align with a respective web 13 of the skirt section 8 and whereas the other leg 16 of each web 14 is disposed parallel to respective pin bosses 6 and the extending ends of the leg 16, joining with the outer end of respective pin bosses as designated at 17. As shown in Figs. 1 and 3, the legs 16 of the webs 14 are spaced 20 from the pin bosses 6 and the extending ends 25 of the legs 15 join the section 9.

Pistons of this improved character are preferably die-cast and in the molding and casting operation, metallic straps of less co-efficient of expansion are inserted in the mold in a manner 30 so that portions thereof will be embedded in the metal of the piston and become a part of the piston. These straps of which there are two pairs, may be of steel and are disposed in the piston above and below the pin bosses, the upper pair of straps designated as 18 each being located in the mold parallel with the thrust axis of the piston and disposed so as to be in abutment with respective webs 13 and the legs 15 of the webs 14. The straps 18 at their ends are provided with bent 35 portions 19 which are embedded in the wall of respective skirt sections 8 and 9 in outwardly curving directions and said straps on their upper and lower edges, intermediate of their ends being beveled as designated at 20, the lower beveled edge of each strap being embedded at 21 in the inner face of each pin boss and on their upper beveled edges being embedded in lower portions 40 of respective supporting legs 5 of the pin 45 bosses as shown in Figs. 1 and 2.

The pair of straps 23 which are disposed beneath the pin bosses, abut respective webs 13 and 14 and are embedded at their ends in the sections 8 and 9 similar to the upper pair of straps 18, 55

said straps 23 intermediate their ends being beveled on their upper and lower edges 24, the upper beveled edge of each strap 23 being embedded in the overlapping portion 25 of each pin 5 boss and being embedded on their lower beveled edges in the overlapping portions 26 which are formed on depending portions 27 of respective pin bosses. Reinforcing lugs 28 over and under engage the upper and lower edges of the straps 10 18 and 23 adjacent their ends.

The skirt section 8 which is on the power thrust side of the piston, it is to be noted, is directly connected to the head by the depending webs 13 which extend to the head and as the webs 13 are 15 disposed at right angle to the pin bosses, the webs 13 are therefore in a direct line of power thrust when the piston is in operation. The webs 14 which support the section 9 from the pin bosses, are not directly connected to the head but are 20 connected to the head through the pin bosses and the pin boss supporting legs 5. Therefore the angular connection of the webs 14 with the pin bosses by the legs 16 of said webs paralleling the pin bosses provide a resiliently yieldable take-up 25 means between the section 9 and its connection with the pin bosses 6 and which means is obviously not a rigid connection as is the webs 13 on the opposite side of the piston with respect to the skirt section 8.

In the operation of a piston of this improved 30 character in the cylinder of an internal combustion motor, after the piston has been previously machined to diameters wherein the skirt 7 which is the guiding or cross head part of the piston is 35 of larger diameter than the head 1 and of a clearance of approximately .002 or less than is the diameter of the cylinder, on expansion of the piston due to heat by reason of the aluminum alloy of the skirt having a greater co-efficient of expansion than the straps 18 and 23, the growing or enlarging of the skirt diameter across the thrust sides or sections 8 and 9 will be held from overexpansion by said straps preventing spreading 40 of said sections owing to the straps having less expansion growth and the required take-up 45 of the expansion across the thrust sides of the skirt will be permitted by the inward drawing of the skirt section 9 occasioned by the resilient yieldable connection of the webs 14 through the flexible legs 16 of said webs which are fulcrumed at 17 to the ends of respective pin bosses 6.

The inward movement of the skirt section 9 50 is brought about by said section being tied to the section 8 by the straps 18 and 23, and during the 55 drawing in movement, said straps are permitted to slide in their places of connection with the pin bosses on their beveled edges and as the skirt section 8 is directly connected to the head through the webs 13, the pulling force of the straps 18 and 23 will therefore be from the power thrust 60 side or skirt section 8 in holding or drawing the flexible skirt section 9 inward.

Obviously constructional modifications of the 65 device are possible without departing from the spirit of the present invention and therefore it is to be understood that it is not necessary to limit the invention by the terms used in the foregoing description, excepting such as the state of the art may require.

70 What I claim is:—

1. A piston having a head and a cross-head

structure connected thereto comprising diametrically opposite skirt sections, pin bosses, right angular resiliently yieldable means joining one of said sections with the pin bosses, said head having a side wall, and webs free from the head side wall 5 and joining said other section with the head and the pin bosses.

2. A piston having a head and a cross-head structure connected thereto comprising diametrically opposite skirt sections, pin bosses, resiliently 10 yieldable means joining one of said sections with the pin bosses, rigid webs depending from the head and joining said other section with the pin bosses, and a pair of transverse members joined at their ends with said sections. 15

3. A piston comprising a head having a skirt and pin bosses, said skirt being flexible on one of its thrust sides and having resiliently yieldable right-angular shaped connection with each pin boss, and a pair of transversely disposed members 20 of different material from the skirt and each abutting a respective right angular shaped connection and joined at their ends with said piston thrust sides.

4. A piston comprising a head having a skirt 25 and pin bosses, said skirt being flexible on one of its thrust sides and having resiliently yieldable right angular shaped connection with each pin boss, and a pair of transversely disposed members 30 of different material from the skirt and each abutting a respective right angular shaped connection and joined at their ends with said piston thrust sides, each of said members having slid-able connection with a respective pin boss.

5. A piston having a head and a cross-head 35 structure connected thereto comprising diametrically opposite skirt sections, pin bosses, resiliently yieldable means joining one of said sections with the pin bosses, webs depending from the head and joining said other section with the pin bosses, 40 and a pair of transverse members of a material different from the skirt sections joined at their ends to said sections and having slidable connection with respective pin bosses.

6. A piston comprising a head, a skirt having 45 opposing thrust sides, pin bosses, integral walls depending from the head and joining the thrust sides of the skirt and the pin bosses, and members of different material from the skirt disposed in paralleling abutment with said walls, said 50 members having their ends embedded in said thrust sides.

7. A piston comprising a head, a skirt having 55 opposing thrust sides, pin bosses, integral walls depending from the head and joining the thrust sides of the skirt and the pin bosses, and members of different material from the skirt disposed in paralleling abutment with the inner ends of the pin bosses and said walls, said members having their ends embedded in said thrust sides. 60

8. A piston comprising a head, a skirt having 65 opposing separated thrust sides, pin bosses, flexible connections from the pin bosses to one of the thrust sides and rigid connections from the pin bosses to the other thrust side, and members of different material from the skirt disposed in paralleling abutment with said connections, said members having their ends embedded in said 70 thrust sides.
